Attorney

UNITED STATES PATENT OFFICE.

GEORGE HANKEL, OF CHICAGO, ILLINOIS.

LOOSE-LEAF BINDER.

Application filed December 10, 1921. Serial No. 521,369.

To all whom it may concern:

Be it known that I, GEORGE HANKEL, a citizen of the United States, residing at Chicago, in the county of Cook and State of Illinois, have invented certain new and useful Improvements in Loose-Leaf Binders, of which the following is a specification.

This invention relates in general to paper files and binders and more particularly to loose-leaf binders, which have transverse cords for holding the loose leaves and means for holding the cords in taut conditions.

One object of the present invention is the production of a loose-leaf binder having a pair of binder strips, one of which has a cord threaded therethrough for holding the cord in a set position, while the other strip is provided with binding clamps for engaging the ends of the cord and holding the same taut.

Another object of this invention is the production of a loose-leaf binder having a transverse cord and binding clamps for engaging the cord and holding the same tautly, the clamps being formed from sheets of material and comprising base plates and clamping levers, with means for holding the levers in set positions.

Another object of the present invention is the production of a simple device, which may be produced at a minimum expense and yet efficiently operate under any conditions and at all times.

One practical form of construction and assembly of the present invention will be hereinafter specifically described and is illustrated in the accompanying drawing, wherein—

Figure 1 is a fragmentary top plan view of the loose-leaf binder, showing the same in an open position and illustrating specifically the construction of the binding clamps.

Figure 2 is a sectional view taken on the line 2—2 of Figure 1, looking in the direction of the arrows.

Figure 3 is a top plan view of one of the binding clamps per se, showing the same in an open condition.

Figure 4 is a longitudinal sectional view through the binding clamp, taken on the line 4—4 of Figure 3.

Figure 5 is a top plan view of the base plate of the binding clamp.

Figure 6 is an inverted detail perspective view of the clamping lever of the binding clamp.

Figure 7 is a sectional view of the binding clamp, taken on the line 7—7 of Figure 3.

Figure 8 is a transverse sectional view of the binding clamp, per se, taken on the line 8—8 of Figure 1.

Referring more specifically to the accompanying drawing by numerals, 10 indicates the backs of the loose-leaf binder, which are connected together by the web 11. No particular novelty is claimed for this part of the disclosure, which is shown merely to illustrate the use of the present invention. It will be noted that the binder strips 12 are connected to the backs 10 at the junction of the backs 10 and web 11 in a flexible manner, as indicated at 13. Therefore, these binder strips 12 are spaced apart and thus provide sufficient space for the positioning therebetween of a number of loose leaves 14, as illustrated in Figure 2.

The binder strips 12 are provided with pairs of aligned openings 15, which are adapted to register with the openings 16 formed in the loose leaves 14. One of the binder strips 12 is provided with a pair of additional openings 17, as shown in Figure 2. A flexible cord 18 is provided and this cord 18 is positioned upon the inner surface of one of the binder strips 12 and is then threaded through the openings 17 of this strip so as to rest upon the outer surface of this strip, and is then passed through the openings 15 of this strip, so that it may then be passed through the openings 16 of the loose leaves 14. It is apparent that the peculiar manner in which the cord is threaded through the openings of the binder strip having the openings 17 prevents the cord 18 from slipping when the loose leaves are being placed within or are being removed from the binder.

A pair of binding clamps are mounted upon the remaining binder strip for the purpose of engaging the free ends of the cord 18 and hold them in taut conditions, thus preventing the loose leaves from being acci-

dentially slipped from the cord or displaced from the loose-leaf binder. As the constructions of the binding clamps are identical, it is thought that the description of one of the clamps will clearly set forth the construction of both and accordingly only one of the clamps will be described.

Each clamp comprises a base plate 19, which is elongated and has at its ends the outwardly extending flat ears 20 having the apertures 21, as shown in Figure 5. An opening 22 is formed in the body of the plate, as is an opening 23, for purposes yet to appear. A stop flange is formed upon one of the longitudinal edges of the base plate as indicated at 24, while an abutment boss 25 extends upwardly from the surface of the plate. The top surface of this boss 25 is cam shaped, while its inner side is vertical and parallel to the stop flange 24. A pin 26 also rises from the surface of the base plate 19 adjacent the edge of the plate opposite to that upon which the stop flange 24 is formed.

A clamping lever 27 is provided and this lever comprises a substantially rectangular body 28, from which extends the elongated arm 29. An opening 30 is formed in the body of the lever in alinement with the arm 29, as shown in Figures 1, 3, and 5, while another opening 31 is formed in the body of the lever, but at the opposite end portion of the body. This clamping lever is mounted upon the base plate 19 and the headed rivet 32 passes through the opening 31 of the body of the clamping lever, through a washer 33 and the opening 23 of the base plate 19, thus pivotally supporting the clamping lever 27. By referring particularly to Figure 7, it will be seen that the washer 33 is interposed between the base plate 19 and the body of the clamping lever, thus spacing this body 28 from the base plate 19, for purposes yet to appear. It should also be noted that a transversely extending lug 34 is formed upon the under side of the arm 29 of the clamping lever and this lug 34 has a cam surface at one side portion thereof, as indicated at 35. This lug 34 normally bears upon the surface of the base plate 19, as shown in Figures 2 and 8.

When the device is in use and it is desired to place some additional loose leaves in the binder, the clamping lever is swung outwardly to the position indicated in Figure 3, its outward pivotal movement being limited by the pin 26. At this time the opening 30 of the lever will be in registry with the opening 22 in the base plate 19. The base plates of the binding clamps are mounted in spaced relation upon one of the binding strips 12 and the base plates are retained in position by rivets 36 which pass through the apertures 21 of the ears 20 and

into the binding strip upon which the binding clamps are mounted. It is obvious that any desirable securing means may be employed for securing the binding clamps upon the binder strips, without departing from the spirit of the invention. By referring to Figure 4 it will be seen that when the binding clamps are in open positions, as indicated also in Figure 3, the openings 30 and 22 are in registry, while the openings 22 of the base plates 19 are at all times in registry with the openings 15 formed in the binder strip upon which the binding clamps are mounted. Therefore, the ends of the cord 18 may be passed through the openings 16 of additional loose leaves 14 and then these ends may be passed through the openings 15 of the binder strip 12 carrying the binding clamps and through the openings 22 and 30 of the two clamps. The cord 18 is then drawn taut, so that the leaves 14 are in their correct position between the backs 10 and the binder strips 12. The clamping levers are then moved to the closed positions indicated in Figures 1 and 2. These clamping levers are formed from sheet metal of such resiliency as to permit the levers, although being secured by the rivets 30, to ride up over the bosses 25. Since the lugs 34 have cam surfaces 35 and the bosses also have cam surfaces, the arms of the levers will readily pass over the bosses 25. When in a final closed position the arms 29 of the levers will each snap into a locked position between the stop flange 24 and the vertical side of the boss 25, as indicated in Figure 8. It is apparent that the flanges 24 limit the rearward swinging movement of the arms 29 of the levers, while the vertical sides of the bosses 25 prevent the levers from accidentally swinging forwardly. Therefore, the clamping levers will be positively held so as to extend longitudinally of the base plates and consequently the openings 30 of the clamping levers will be held out of alinement with the openings 22 of the base plates 19. This action of the binding clamps will cause the ends of the cords to be turned over upon the surfaces of the base plates 19, whereby the portions of the ends of the cord 18 which rest upon the plates 19 will be extending acutely to the portions extending through the openings 22 of the base plates 19 and the portions of the ends of the cord extending through the openings 30 of the clamping levers. Sufficient space is provided between the levers and the base plates to prevent the cutting of the cord, while the manner in which the ends of the cord 18 are drawn acutely over the edges of the plates and the levers surrounding the openings 22 and 30 respectively absolutely prevents the cord from slipping. When the clamping levers are in locked positions and the cord 18, as a result, is being held in a

taut condition, the loose-leaf binder may be opened and closed as much as may be desired without danger of the cord becoming loose and permitting the disarrangement of the levers 14.

When it is desired to open the binding clamps, so as to free the ends of the cord 18, the outer ends of the arms 29 of the clamping levers 27 may be gripped from beneath, since the outer ends of these arms are turned up slightly for facilitating this action, and the resiliency of the arms permit them to be raised slightly so that the lugs 34 may clear the upper portions of the bosses 25, whereby the levers 27 may be swung outwardly until they strike the pins 26. At this time the openings 30 of the levers will be in registry with the openings 22 in the base plates 19, thus allowing the withdrawal of the ends of the cord 18. Leaves 14 may then be placed upon or removed from the ends of the cord, whereupon the ends of the cord may again be passed through the openings 22 of the base plates 19 and through the openings 30 of the clamping levers 27 and the clamping levers moved to the closed positions as above set forth, so that the cord will be again gripped and held in a taut condition, so that the loose-leaf binder may be properly and readily used.

Since the washers 33 space the bodies of the levers from the surfaces of the base plates 19, while the lugs 34 engage the surfaces of the plates, it is apparent that the bodies and arms of the levers 27 will be held spaced from the base plates at all times. Therefore, it is impossible for the levers to cut the cord, although they will firmly grip the cord to hold the same from slipping. It is also apparent that the stop flanges and the bosses positively hold the levers 27 from accidental movement.

From the foregoing description it is apparent that a very simple and efficient improvement in loose-leaf binders has been produced. The binding clamps may be formed from blank sheets of metal, being stamped to form the construction described, which after being assembled, will positively and properly operate, since their simplicity of construction precludes the possibility of complications which exist when more complicated devices are used. Their constructions also permit them to be produced at a minimum cost, which is an important feature of the invention, from a commercial viewpoint. The device is easily operated, since it is only necessary to lift and then swing the levers outwardly so as to permit the ends of the cord to be withdrawn or to move the levers so as to ride over the bosses and fit between the bosses and the stop flanges, in order to bind the cord 18 and hold the loose leaves in their correct positions.

65 While one practical form of construction

and assembly of the present invention has been illustrated and described, it is obvious that the right is reserved to make various changes in the detail construction, as long as such changes do not exceed the scope of the invention as claimed, and for this reason the invention is not limited to the specific construction hereinbefore described.

The invention having been described, what is claimed as new is:

1. In a device of the character described, the combination of a support, binding clamps mounted upon said support, each clamp comprising a base plate having a clamping lever pivotally mounted thereon, said plates having receiving portions, said levers being adapted to be moved so that the receiving portions thereof will move into and out of registry with the receiving portions of the base plates, means for releasably holding the levers in set positions when the receiving portions thereof are out of registry with the receiving portions of the base plates, and a cord carried by said support and engaging the receiving portions, as and for the purposes set forth.

2. In a device of the character described, the combination of a support, binding clamps mounted upon said support, each clamp comprising a base plate having a clamping lever pivotally mounted thereon, said plates and said levers having receiving portions, said levers being adapted to be moved so that the receiving portions thereof may move into and out of registry with the receiving portions of said base plates, means for limiting the movement of said levers when they are moved so that the receiving portions thereof are in registry with the receiving portions of said plates, means for releasably holding the levers in set positions when the receiving portions thereof are out of registry with the receiving portions of the base plates, and a cord carried by said support and engaging the receiving portions, as and for the purposes set forth.

3. In a device of the character described, the combination of a support, binding clamps mounted upon said support, each clamp comprising a base plate having a clamping lever pivotally mounted thereon, said plates and said levers having receiving portions, means for spacing said levers from the surfaces of said plates, said levers being adapted to be moved so that the receiving portions thereof will move into and out of registry with the receiving portions of said plates, and a cord carried by said support and engaging the receiving portions of said plates and said levers, as and for the purposes set forth.

4. In a device of the character described, the combination of a support, binding clamps mounted upon said support, each clamp comprising a base plate having a

clamping lever pivotally mounted thereon, said plates and said levers having receiving portions, said levers being adapted to be moved so that the receiving portions thereof will move into and out of registry with each other, washers interposed between said levers and said base plates, lugs formed upon said levers and engaging the surfaces of said base plates, whereby the levers are spaced from the surfaces of said base plates, and a cord carried by said support and engaging the receiving portions of said base plates and said levers, as and for the purposes set forth.

ried by said plates in the path of movement of said levers when the levers are swung in one direction to automatically aline the receiving portions of said levers with the receiving portions of said base plates, stop 70 flanges formed upon the rear side edges of said base plates, bosses formed on the surfaces of said base plates, the upper surfaces of said bosses being cam shaped, said bosses also having vertical inner sides which are 75 parallel to said stop flanges, said levers being adapted to be received between the flanges and bosses when the receiving portions thereof are out of registry with the receiving portions of said base plates, and a cord carried 80 by said support and engaging the receiving portions of said levers and plates, as and for the purposes set forth.

15. 5. In a device of the character described, the combination of a support, binding clamps mounted upon said support, each clamp comprising a base plate having a clamping lever pivotally mounted thereon.

20 said plates and said levers having receiving portions, said levers being adapted to be moved so that the receiving portions thereof may move into and out of registry with the receiving portions of said plates, step

25 the receiving portions of said plates, stop flanges formed upon the rear edges of said base plates, bosses formed on the surfaces of said base plates, the upper surfaces of said bosses being cam shaped, said bosses also having vertical inner sides which are par-

30 having vertical inner sides which are parallel to said stop flanges, said levers being adapted to be received between the flanges and bosses when the receiving portions thereof are out of registry with the receiving portions of said base plates, and a cord 35 carried by said support and engaging the receiving portions of said levers and plates, as and for the purposes set forth.

6. In a device of the character described, the combination of a support, binding

40 the combination of a support, binding clamps mounted upon said support, each clamp comprising a base plate having a clamping lever pivotally mounted thereon, said plates and said levers having receiving portions, said levers being adapted to be

45 portions, said levers being adapted to be moved so that the receiving portions thereof may move into and out of registry with the receiving portions of said plates, pins carried by said plates in the path of movement of said levers when the levers are

50 ment of said levers when the levers are swung in one direction to automatically align the receiving portions of said levers with the receiving portions of said plates, and a cord carried by said support and engaging the receiving portions of said levers and plates, as and for the purposes set forth.

7. In a device of the character described, the combination of a support, binding clamps mounted upon said support, each clamp comprising a base plate having a clamping lever pivotally mounted thereon, said plates and said levers having receiving portions, said levers being adapted to be moved so that the receiving portions thereof may move into and out of registry with the receiving portions of said plates, pins car-

8. In a device of the character described, the combination of a support, binding 85 clamps mounted upon said support, each clamp comprising a base plate having a clamping lever pivotally mounted thereon, said plates and said levers having receiving portions, said levers being adapted to be 90 moved so that the receiving portions thereof may move into and out of registry with the receiving portions of said plates, pins carried by said plates in the path of movement of said levers when the levers are swung in 95 one direction to automatically aline the receiving portions of said levers with the receiving portions of said base plates, stop flanges formed upon the rear side edges of said base plates, bosses formed on the surfaces of said base plates, the upper surfaces of said bosses being cam shaped, said bosses also having vertical inner sides which are parallel to the stop flanges, said levers being adapted to be received between the flanges 100 and the bosses when the receiving portions thereof are out of registry with the receiving portions of said base plates, washers interposed between the levers and said plates, lugs formed upon the lower surfaces of said levers, said lugs engaging said plates, whereby the levers are spaced from said plates, and a cord carried by said support and engaging the receiving portions of said levers and said plates, as and for the purposes set forth. 110 115

9. In a device of the character described, the combination of a support, binding clamps upon said support, each clamp comprising a base plate having a clamping lever pivotally mounted thereon and 120 swinging in a horizontal plane thereabove, said plates having receiving portions, said levers having receiving portions, said levers being adapted to be moved so that the receiving portions thereof will move into and 125 out of registry with the receiving portions of the base plates, and a cord carried by said support and engaging the receiving portions, and for the purposes set forth. 128

10. In a device of the character described, 130

the combination of a support, binding clamps mounted upon said support, each clamp comprising a base plate having a clamping lever pivotally mounted thereon, 5 said plates having receiving portions, said levers having receiving portions, said levers being adapted to be moved so that the receiving portions thereof may move into and out of registry with the receiving portions of 10 said base plates, means carried by said plates

in the paths of movement of said levers for limiting the movement of said levers when they are moved so that the receiving portions thereof are in registry with the receiving portions of said plates, and a cord carried by said support and engaging the receiving portions, as and for the purposes set forth. 15

In testimony whereof I affix my signature.
GEORGE HANKEL.
